UNITED STATES PATENT OFFICE.

JAMES H. RAND, OF NORTH TONAWANDA, NEW YORK, ASSIGNOR, BY MESNE ASSIGNMENTS, TO REMINGTON RAND INC., OF NEW YORK, N. Y., A CORPORATION OF DELAWARE.

INDEX.

Application filed April 14, 1922. Serial No. 552,791.

This invention relates to index devices of the type having movable index holders or panels for displaying the classified subject-matter of the indexes and more particularly to that type in which the index holders are mounted to swing in vertical planes into and out of a cabinet in which a plurality of such holders are arranged in juxtaposition.

10 Objects of the invention are to arrange such holders to be completely housed within a cabinet as a protection from dust and defacement, to permit the holders to swing to an inclined position before the cabinet 15 for the convenient entry of index inscriptions, to arrange the holders to move downwardly and outwardly to extended position outside the cabinet and then to open in book form, to provide an index device which 20 slides upwardly into the cabinet with little effort on the part of the user, and in general to improve prior devices of this character and render them more convenient and accessible for use.

25 For the purpose of illustration one concrete embodiment of the invention is shown in the accompanying drawings, in which:—

Fig. 1 is a perspective view;

Fig. 2 is an end elevation showing the 30 cabinet in vertical section;

Fig. 3 is a view similar to Fig. 2 to enlarged scale and showing a vertical section through the book index;

35 Fig. 4 is an enlarged plan view, partly in section, of a detail of the parts shown in Fig. 1;

Fig. 5 is a section on the line 5—5 of Fig. 3; and

40 Fig. 6 is a section on the line 6—6 of Fig. 3.

The embodiment of the invention shown for the purpose of illustration comprises a cabinet A constructed of any suitable material, preferably sheet metal, and having one 45 side open. As shown in the sectional views in Fig. 2 and Fig. 3, the sheet metal parts forming the cabinet are preferably constructed with inturned ends provided with bent marginal portions forming 50 flanges. Top and bottom members a and b are thus similarly constructed with a flange c and are attached to the back d of the cabinet by angle members e. Ends f likewise are formed with a flange c and the

flanges at their meeting points may be 55 united in any suitable manner as by welding to form a finished joint.

Extending transversely through the cabinet adjacent the rear wall d and approximately midway between the top and bottom 60 is a rod or shaft g which serves as a pivot for a plurality of links h, to the free end of which are pivotally mounted index holders of any desired form for swinging movement into and out of the cabinet. The links 65 h are normally maintained in vertical position within the cabinet by the provision of coil springs i coiled about shaft g, each having one end in abutting relation with rear wall d and the other fast in an opening j 70 in the corresponding link (Fig. 3). Stop means for limiting the downward swinging movement of links h is provided in the form of a bar k. To properly support shaft g and stop k and to guide the links h in their 75 swinging movement a plurality of narrow partitions l are provided adjacent the rear wall d of the cabinet, the shaft extending through perforations therein and the stop k being notched therein as indicated in 80 Figs. 2 and 3.

While any suitable or desired type of index holder may be mounted upon the links h the preferred form is a book index device comprising a back m to which a plurality of 85 panels n are hinged in any suitable manner. The back and panels are preferably constructed of sheet material such as sheet aluminum, the back being of U-shape in transverse section as shown in Fig. 4 and having 90 free edges slotted and rounded as indicated at m' to provide a pivot opening for a hinged connection with the panels n which are similarly slotted and rounded to receive pivots n'. Adjacent the upper end of the back a pivot pin o is transversely disposed and connects the back to the corresponding link h, a slot p being provided to receive the adjacent portion of the link as the book index is moved to housed position within the 100 cabinet. To prevent excessive looseness or play about the pivot of the link h about the pivot pin o washers or spacers o' may be provided upon the pivot on either side of the link as indicated in Fig. 4.

105 The form of book index shown has two panels or leaves n hinged to the free edges of the back end. These panels or leaves

have their marginal portions rounded over into parallel relation with the body of the panel or leaf and then bent at 90° into abutting relation therewith, thus forming hollow 5 marginal flanges *q* on the top, bottom and free edge. In the space defined by these integral marginal flanges and by the hinged connection to the back *m* are provided means for removably mounting index material in 10 the form of cards or strips. One means for mounting such material comprises an elongate strip *r* (Fig. 6) preferably of metal, the ends of which are received and held in place by the flanges *q* at the top and bottom 15 of the index panels as shown in Fig. 5. Upon the side edges of strips *r* are mounted elongate spring clips *s* (Fig. 6), preferably bent from a single strip of sheet metal and adapted to retain under their rounded spring 20 ends index strips or rails *t* of any suitable or desired type. These strips or rails may have index cards *t'* hinged thereto in a known manner as indicated in Fig. 5. To suitably indicate the nature of the index material within the book index tabs *u* may be 25 attached to the marginal flanges *q* in any desired manner in a convenient position to be used as grips for swinging the book index into extended or exposed position for inspecting the classified index material thereon.

For convenience in using the herein described device the cabinet *A* housing the same is preferably mounted upon the horizontal portion *v* of the top of a desk *B* of 35 usual construction, the top being provided with a downwardly inclined portion *w* having a strip of moulding *x* attached thereto to form a ledge serving as a stop for the lower end of the book indexes. For easy 40 sliding movement over the inclined surface *w*, the lower portion of the back of each of the book indexes is preferably beveled as indicated at *y*.

The book indexes are normally disposed in 45 completely housed position within the cabinet *A*, where they are protected from dust and injury. In use the operator grasps the projecting tabs *u* of the required index and pulls upon the latter swinging the book index downwardly and outwardly against the tension of spring *i*, the beveled lower end *y* of the back sliding upon the inclined surface *w* until it engages stop *x*, the link *h* at 50 the same time engaging stop *k*. The book index is now in the position shown in Fig. 2, and the leaves of the index now being completely outside of the cabinet may be 55 opened to the position shown in Figs. 1 and 4 for the convenient inspection of the index material thereon or for the entry of new data or for making changes or substituting new index cards or strips. When the entries or changes are completed the leaves of the book index are closed and the latter is swung 60 upwardly with the link *h*, very little effort

being necessary to return it to housed position by reason of the action of spring *i*.

I claim:

1. An index device comprising a cabinet, an index holder normally housed within said cabinet, and a rigid member less in length than the height of the holder pivoted at one extremity to the cabinet and at its other extremity directly to the holder, and constructed and arranged to guide the holder 70 when moved outwardly from the cabinet. 75

2. An index device comprising a cabinet, an index holder normally housed within the cabinet, and an elongate member pivoted at one extremity to the holder adjacent to the top thereof, and at its other extremity to the 80 interior of the cabinet at a point substantially midway of the height of the latter.

3. An index device comprising a cabinet, an index holder housed therein, a rigid 85 member pivoted to said holder and said cabinet respectively to permit the former to be swung to a position outside said cabinet, and means tending to maintain said member in position to retain said holder 90 within said cabinet.

4. An index device comprising a cabinet, an index holder housed therein, a link pivoted at its opposite ends to the upper end 95 of the holder and to the cabinet respectively to permit the holder to be swung to a position outside of the cabinet, yielding means normally tending to retain the holder within the cabinet, and an inclined guide for the lower end of the holder. 100

5. An index comprising a cabinet having an open front, a transverse shaft adjacent to the back of the cabinet, a rigid link pivotally mounted upon the shaft, an index holder normally housed within the cabinet, 105 pivot means connecting the holder with the link, and means tending to prevent movement of the link and holder from normal position.

6. An index comprising a cabinet having 110 an open front, a substantially rigid link pivoted at one end at a point adjacent to the rear wall of the cabinet and substantially midway of the height of the latter, an index holder normally housed in upright 115 position within the cabinet, and means pivotally connecting the other end of the link to the upper end of the holder.

7. An index comprising a cabinet open 120 at its front, an index holder normally housed in upright position within the cabinet, a link having one end pivotally secured to the upper end of the holder, a pivot member connecting the other end of the link to the cabinet, and a spring normally tending 125 to prevent withdrawal of the holder from the cabinet.

8. An index comprising a cabinet open 130 at its front, a shaft extending transversely of the cabinet adjacent to its rear wall, a

link having an opening adjacent to one end for the passage of the shaft, a spring encircling the shaft and normally tending to hold the link in substantially vertical position, a 5 holder normally disposed within the cabinet, and pivot means connecting the opposite end of the link to the upper end of the holder.

9. An index comprising a cabinet having an open front, a plurality of holders within 10 the cabinet, a shaft extending transversely of the cabinet, a link corresponding to each holder, one end of the link being pivoted to the holder and the other pivoted upon the shaft, and a plurality of coiled 15 springs encircling the shaft, one spring being connected to each link and reacting upon the latter to tend to retain it with its corresponding holder within the cabinet.

10. An index comprising a cabinet having an open front, an index holder normally positioned vertically within the cabinet, a link connecting the upper rear corner of the holder with the cabinet, and a stop member disposed in the path of the link and 25 limiting movement of the upper rear corner of the holder substantially to a quadrant of arc.

11. An index device comprising a cabinet having one open side, a downwardly inclined 30 surface before said open side, an index holder mounted in said cabinet, guide means connecting the holder and cabinet constructed and arranged to permit outward and downward movement of the holder 35 through said open side of the cabinet, the lower rear portion of said holder being beveled for sliding contact with said inclined surface, and stop means for limiting movement of the lower end of the holder over said inclined surface.

12. An index comprising a cabinet having an open front, an index holder having a 40 back member, normally housed within the cabinet with its back member substantially 45 vertical, means connecting the upper end of the back member to the cabinet and constraining such upper end to move in an arcuate path, and stop means limiting such movement substantially at the instant that 50 the upper end of the back member has reached the plane of the open front of the cabinet.

13. An index comprising a cabinet having a rear wall and an open front, an index 55 holder comprising a back and a plurality of panels hinged thereto, the holder nor-

mally being housed in upright position within the cabinet with its back adjacent to the rear wall of the latter, means connecting the upper end of the back of the holder to the cabinet and guiding such upper end to move in an arcuate path, and means for guiding the lower end of the holder in a 60 forwardly and downwardly inclined path.

14. An index device comprising a cabinet 65 having an open side, a plurality of index holders each comprising a back and panels hinged thereto, said holders normally being housed in upright position within the cabinet with their backs adjacent to the rear wall 70 of the cabinet, and means connecting the upper end of each holder to the cabinet for guiding and controlling each holder to permit the holder to move as a unit out of such cabinet with the bottom of the holder moving 75 away from the base of the cabinet and its top supported adjacent to and within the open side of the cabinet, the panels being capable of swinging open upon their hinged connections to the back of the holder when 80 in extended position.

15. An index, comprising a cabinet having an open front, a support projecting forwardly from the front edge of the cabinet, an index holder independent of the cabinet 85 removably housed in upright position therein and movable outwardly onto said support in inclined position with the lower end engaging the support, and guide means connecting the holder to the cabinet for guiding and supporting the upper end thereof.

16. An index, comprising a cabinet having an open front, a support projecting forwardly from the front edge of the cabinet, an index holder independent of the cabinet 95 removably housed in upright position therein and movable outwardly onto said support, and guide means for the upper end of the holder.

17. An index, comprising a cabinet having an open front, a support extending forwardly from the bottom front edge of said cabinet, an index holder independent of the cabinet and normally housed in upright position therein, guide means for the upper 100 end of the holder, and means on the holder having guiding and supporting cooperation with the support.

Signed by me at Boston, Mass., this 20th day of March, 1922.

JAMES H. RAND.
